UNITED STATES PATENT OFFICE.

FREDERICK BOWYER HOLLIS, OF LONDON, ENGLAND.

GOLF TEE.

Application filed June 6, 1925. Serial No. 35,485.

To all whom it may concern:

Be it known that I, FREDERICK BOWYER HOLLIS, a subject of the King of Great Britain, residing in London, England, have 5 invented certain new and useful Improvements in Golf Tees, of which the following is a specification.

The object of this invention is to provide a golf tee which will assist the player to 10 strike the ball accurately, and with this object there is provided in association with the tee itself upon which the ball is placed a small disc which, when the ball is placed upon the tee, assumes or is given a position 15 directly in rear of the point of the ball which is struck by the club when an accurate shot is made. The player, when addressing the ball, has this disc or spot, to which any suitable colour or marking or shape can be 20 given, to concentrate his vision upon, and is thereby assisted not merely to keep his eye on the ball but as nearly as may be upon that spot of the ball which the club head should strike. It is, of course, impossible for the 25 player to keep his eye on that definite point on the ball which is to be struck, since the position of the point is substantially at the end of the horizontal fore and aft diameter, but the present invention provides a well defined spot directly in rear of the correct 30 point of impact and thereby assists the player to make an accurate shot.

One embodiment of the invention is illustrated in the accompanying drawings, 35 wherein Figs. 1 and 2 are respectively an elevation and plan view of the improved tee in the collapsed condition as carried by the player; Figs. 3 and 4 are respectively a rear elevation and a plan of the tee as placed 40 upon the ground in position to receive the ball; and Figs. 5 and 6 are respectively a side elevation and plan of the tee and ball in the striking position.

As therein shown the support or tee prop- 45 er is a hollow parallelepiped A, which is usually of paper of sufficient stiffness, but may be of any other suitable material, with- out top or bottom and of such depth and size of aperture that when the ball B is 50 placed upon it, the latter is at the appropriate height for striking. The height of the

ball with respect to the ground may be varied by varying either the length of the side of the parallelepiped or its depth, and the tee can be made and issued in various 55 standard dimensions, according as a low, medium or high tee is required by the player.

Integral with or attached to the rear wall of the tee is a strip C of paper, or other suitable thin and preferably slightly spring 60 material, extending vertically upward from the centre of the wall and having at the free end a round or other shaped disc C' of suitable size which may be coloured or otherwise marked on its front face to assist concentra- 65 tion of vision upon it. It will be convenient to refer to the marked face of this disc as the eye-spot. When the ball is placed upon the tee, as shown in Fig. 5, the strip C is deflected rearwardly in the vertical fore and 70 aft plane and thereby brings the eye-spot into an approximately horizontal position directly behind the rear central point of the ball. Should it be desired the disc C' may be turned downwards by the fingers to give 75 it a more horizontal position, as shown in Fig. 5, than it would assume merely by the flexure of the strip C upon placing the ball on the tee. It is not, however, necessary that the eye-spot should be in the horizontal 80 plane through the center of the ball so long as it is clearly directly in rear of the ball in the fore and aft vertical plane and visible to the player.

Instead of the aperture of the box-shaped 85 tee being square, as shown, it may be polygonal or circular or any other suitable shape, the shape and material being preferably of such a character as to enable the tee readily to assume a compact collapsed 90 form.

The box tee A and also the strip C are preferably green in colour, for reasons ob- 95 vious to golfers, while the eye-spot is col-oured or otherwise marked to make it stand out as clearly as possible to the vision.

Having thus described the nature of the 100 said invention and the best means I know of carrying the same into practical effect, I claim:—

1. A golf tee comprising a collapsible body portion and an eye-spot associated

therewith and arranged to be deflected by the placing of the ball on the body portion of the tee into an appropriate position clearly visible to the player.

2. A paper golf tee comprising a body portion in the form of a top-less parallelepiped and an eye-spot formed on a strip extending vertically upwards from the rear face of said body portion.

3. A golf tee comprising a hollow body portion upon which the ball rests and an eye-spot connected therewith and extending above the top of the body portion and laterally thereof.

In testimony whereof I have signed my name to this specification.

FREDERICK BOWYER HOLLIS.
